GAS LIFT OPERATION IN A MOVING BED CONVERSION OF HYDROCARBONS

John W. Delaplaine, Swarthmore, Pa., assignor to Houdry Process Corporation, Wilmington, Del., a corporation of Delaware

Application April 17, 1951, Serial No. 221,405

6 Claims. (Cl. 196—52)

The present invention relates, in general, to the operation of systems for elevating granular material through an upright conduit, such as a lift pipe, by means of a gas stream, and is particularly directed to a method for effecting elevation of granular material by the lift gas under conditions obtaining high efficiency and reduced attrition of the granular material. Although not limited thereto, the invention finds important application in the elevation of a granular contact mass, such as catalyst, in a hydrocarbon conversion system, wherein the contact mass is continuously circulated through a downflow path comprising one or more processing zones and is thereafter returned to the top of said path by a gas lift.

Granular contact material, such as catalyst, which may be in the form of cylindrical pellets or substantially spherical beads, is subject to attrition by impact and abrasion, and because the material is in continuous circulation, the formation of a large quantity of fines as a result of such attrition presents a major problem.

Since the efficient handling of hydrocarbon conversion catalyst is a principal object of the invention, in the description which follows this material is specifically referred to as typical, but it will be understood that the invention is not limited thereto.

In the moving bed type of hydrocarbon conversion process, relatively large particles or granules, such as sized pieces, pellets, formed spheres and the like ranging in size from about 0.05 to 0.5 inch in diameter flow principally or solely under the influence of gravity through a downflow path or paths of a system in which there are one or more processing zones wherein the granular solids are contacted with fluids which are converted by contact with the granular solids and/or which are utilized in treating the granular solids. The gravitational flow of solids through such processing or treating zones is principally or solely as compact downwardly moving non-turbulent beds. Such systems are discussed generally in "The 'T. C. C.' catalytic cracking process for motor gasoline production" by R. H. Newton, G. S. Dunham, and T. P. Simpson, "Transactions of the American Institute of Chemical Engineers," volume 41, page 215, April 25, 1945, and the articles there cited.

In such a moving bed type of system, it has been found advantageous to transport the solid particles (i. e., catalyst or other contact material) by one or more pneumatic or gas lifts which serve as an upflow path or paths. The system may comprise a single downflow path in which there are several process zones at different heights through which zones the contact material flows consecutively so that the solid particles need be transported by the gas lift only once in a complete cycle of operation or the system may comprise a plurality of gas lifts and/or downflow paths each containing a single process zone. An exemplary system of the former type has been described in an article entitled "Houdriflow: new design in catalytic cracking," appearing in the "Oil and Gas Journal," page 78, January 13, 1949.

When catalyst is introduced into the gas stream at the

bottom of a lift, the transfer of momentum from the fluid to the catalyst is not instantaneous. A certain portion of the lift is traversed by the catalyst before it reaches, or more accurately, closely approaches its equilibrium velocity which is attained when the only remaining driving force for acceleration of the catalyst is that due to changing static pressure with lift height. Since the fluid density varies directly with the pressure of the gas, it will be seen, that as the gas pressure decreases the linear velocity of the fluid is correspondingly increased causing a further acceleration of the catalyst in the lift conduit. Accordingly, even in the absence of heat exchange between catalyst and gas, the catalyst is moved through the lift path with progressively increased velocity, so that in lifts of a height required in commercial practice, fairly high linear velocities may be reached under normal operating conditions in lifting solid granular particles, such as catalyst, of the size range herein contemplated. At high catalyst velocities, it has been found in practice, increased catalyst attrition results.

Efforts to reduce the extent of acceleration of catalyst in the lift conduit, for instance by uniformly tapering the lift conduit outwardly in the direction of travel of the catalyst have not met with the expected success and in many instances erratic operation resulted as opposed to desired substantially smooth straightline flow that can be obtained in a lift conduit of substantially uniform diameter.

The total pressure drop required to produce a certain catalyst circulation at a given rate of fluid introduction can be mathematically predicted. The pressure drop efficiency of a particular lift system is the quotient of the calculated lift pressure drop divided by the actual pressure drop obtained in operation of the lift. Since, in most commercial units the desired conditions are close to the maximum available pressure and maximum allowable catalyst velocity, when lower than normal efficiency is encountered on the basis of pressure drop considerations, it means that the lift is operating to circulate catalyst at a rate materially below calculated design and expectation. Low lift pressure efficiency, moreover, is often indicative of unsteady or erratic flow at one or more regions along the lift path, which may be a major cause of abnormal catalyst attrition. It will be seen, therefore, that raising the gas inlet pressure does not afford a practical solution to the problem, even if this were possible and were not otherwise economically prohibitive.

It has now been found that improved lift operating efficiency is obtained by the use of lift gas which at the zone of initial engagement therewith is at a temperature substantially higher than that of the catalyst. Moreover, by the use of the hotter gas in accordance with the invention, the normal tendency for reduction in fluid density due to progressive pressure drop in the lift (and the consequent increase in gas velocity accompanied by increased catalyst velocity) is largely compensated or offset by transfer of sensible heat from the lift gas to the catalyst, thereby reducing the temperature of the gas and increasing its density. Under these conditions of improved operating efficiency a more uniform velocity is obtained over the major portion of the lift path and there is less tendency for occurrence of regions of unstable flow within the lift.

While heat transfer between transporting gas and granular material having a temperature differential therebetween is quite rapid, it is not instantaneous. Precise mathematical calculations of the rate of incremental heat transfer along the lift path cannot be made on the basis of concepts developed from fundamental studies of heat transfer relationships in fluid dynamics in view of the paucity of reliable information on the behavior of such systems, but empirical data obtained in the development

of the present invention are adequate for all practical purposes in establishing the operative conditions and techniques for commercial adaptation of the invention.

The invention will be understood from the detailed description which follows read in connection with the accompanying drawings illustrating schematically in Figures 1 and 3 embodiments of typical systems to which the invention applies; Figure 2 is a partial view illustrating one form of heater that may be used for heating the lift gas.

Referring now particularly to Figure 1 there is shown a typical system suitable for use in hydrocarbon conversion operations, such as cracking, in contacting fluids with granular solid materials, of the type employing compact gravitating beds of such granular materials in the fluid contacting zones. The system comprises principally a convertor vessel or reactor indicated generally at 10 through which the solid contact material flows as a downwardly moving non-turbulent bed, and is transferred through a conduit 11 to a regenerator vessel or kiln indicated generally at 12, in which the carbonaceous deposit formed on the solid material in the reactor, is removed. The granular material may be an inert substance utilized for its heat transfer capacity, but in the more general case the granular material is catalytic in nature. Compositions effective as hydrocarbon conversion and/or cracking catalysts (typically natural or synthetic aluminosilicate) and the conditions employed for conversion of hydrocarbons in reactor 10 and for regeneration of the catalyst in kiln 12 are well known to the art and need not be repeated here.

Regenerated catalyst particles are withdrawn from kiln 12 and flow downwardly in conduit 13 as a compact non-turbulent column to a gas lift engager or transfer chamber, indicated generally at 14, from which the catalyst is lifted and transported vertically upward as a continuous stream of solid particles by a transporting or lifting gas introduced into the transfer hopper 14.

Under the impelling influence of the lifting gas, the catalyst is introduced into and transported through the lift conduit 15, which extends from within the transfer hopper 14 and upwardly through the top thereof to a point of discharge at an elevation above that of reactor 10. The catalyst is discharged from conduit 15 into an enlarged separating or disengaging chamber 16, where as a result of the expanded area, the catalyst separates out from the gas stream and drops to the bottom of the chamber. From the chamber 16 the catalyst is withdrawn by a conduit 17 for return directly to the top of reactor 10; or if desired, the catalyst may be sent to an intermediate surge hopper supplying that reactor.

In the embodiment illustrated in Fig. 1, the catalyst entering the hopper 14 assumes an angle of repose as shown at 18, constituting the top level of the bed of catalyst accumulated in that hopper. Lift conduit 15 extends downwardly into the hopper 14 to a level below that of the catalyst therein. A sleeve 19 surrounds the lift conduit within hopper 14 and extends downwardly into the hopper to approximately the same level as the bottom of the lift conduit 15. The sleeve 19 is closed at the top thereof and open at the bottom so as to form an annular gas-passing space 20 between the outside of the lift conduit and the internal wall of the sleeve. A gas supply line 21 is provided to supply gas to the annular space 20 for downward flow therein. An annular baffle member 22 is arranged within the hopper 14 inwardly from the wall thereof and at a level intermediate the top of the catalyst bed and the bottom of the lift conduit, so that catalyst flowing over the baffle will be directed outwardly at an angle at the inner edge of the baffle to provide a solids-free space or plenum below the baffle. A second gas supply line 23 communicates with the plenum under the baffle.

By the particular gas inlet arrangement above described, the rate of flow of solids into the lift conduit 15

can be readily controlled over a wide range. The lift operation is extremely sensitive to the flow of relatively minor quantities of gas in a direction concurrent to the lateral flow of solids toward the mouth of the lift pipe, so that by the introduction of relatively small quantities of lift gas through supply line 23, a substantial increase in the solids flow rate is obtained. In practice, the primary or principal quantity of lift gas, as about 60-70% or more of the total volume of lift gas introduced into the hopper 14, is supplied by line 21 through the sleeve 19, the remainder being supplied at least in part through line 23 as a secondary stream. If desired, secondary gas may be introduced through line 24 at the bottom of hopper 14, in lieu of or in addition to that introduced through line 23. The outlet of line 24 is surmounted by a cap or screen 25 to prevent solids from falling into that line during periods when gas flow therethrough may be cut off. The stream of lift gas discharged through line 24 is directed upwardly toward the mouth of the lift pipe, which is separated from the discharge outlet of line 24 by a gap of sufficient vertical height to permit the formation of a relatively static layer of solids between the bottom of the lift and the outlet of pipe 24. Within this relatively static layer, there is no substantial lateral movement of the solid particles, although portions thereof may continuously pass upwardly out of the layer into the stream of primary gas discharged through the sleeve and enter therewith into the lift conduit 15, being replaced in the bed by downwardly moving solids. For a given quantity of lift gas, control of the solids flow rate is obtained by dividing the total flow of lift gas between the primary stream introduced through sleeve 19 and the secondary stream or streams introduced through line 23 or 24, or both. These various streams of gas may be the same or different in kind.

In operation of the system thus far described, the catalyst gravitating through the reactor 10 is contacted with hydrocarbons, which may be supplied in vapor or mixed phase, or both. Thus, hydrocarbon vapors may be supplied for concurrent flow through the reactor by a line 26 and reaction vapors removed from the bottom of the reactor by discharge line 27. To maintain desired pressure differential between the disengaging chamber 16 and reactor 10, seal gas is introduced into the column of catalyst flowing through conduit 17 as by means of a line 28 supplying steam or other inert gas above the reactor bed. Below the level of withdrawal of the hydrocarbon reaction vapors from reactor 10, a purge zone is provided, into which steam or other inert gas is introduced through a line 29 communicating with the zone.

The spent catalyst discharged from reactor 10 into the regenerator 12 through seal conduit 11, is contacted with oxygen-containing gas in the regenerator to burn off combustible deposit. In the embodiment diagrammatically represented in Figure 1, for instance, the oxygen-containing gas is introduced into the regenerator by lines 30 and 31 and combustion products in the form of flue gas removed therefrom by lines 32 and 33.

In practice of the invention there is no particular limitation as to the kind of gas or vapor that can be employed as lifting medium. Conveniently flue gas discharged from the kiln 12 or from a selected zone thereof may be sent to the transfer hopper 14 for use as lift gas therein, and the flue gas may be supplemented by steam or other inert or compatible gas from other sources.

In certain cases it may be preferred to operate with cross flow gas introduced through line 23 instead of diffuser gas supplied through line 24 as the secondary gas supply; however, by their joint use the range of flexibility and control is beneficially extended.

Where gas from an independent source is employed as lift gas, it will be understood, that gas may be heated to any desired temperature above that of the catalyst, in practice of the invention. In using flue gas discharged from kiln 12 as the lift medium, ordinarily, such gas will

not have the desired temperature higher than that of the catalyst discharged from the kiln and admitted to the transfer hopper 14. In order to obtain the desired high temperature in the lift gas for practice of the present invention, suitable arrangements will ordinarily be necessary for raising the temperature of the flue gas to that required. A convenient method and device for heating the flue gas to the desired temperature is by the use of an air-line burner such as diagrammatically illustrated in Figure 2. A suitable gaseous fuel, such as propane, is ignited and burned at the tip of a jet 34 within an enclosed housing 35, and in an atmosphere of air supplied through a pipe 36 surrounding the jet. A cylindrical partition 37 extends part way up into the housing 35 and is spaced from the wall thereof to provide the boundaries for a combustion chamber 37a which is open at the top. Flue gas to be heated is admitted through a conduit 38 communicating with the space between the partition 37 and the wall of housing 35. In operation, the hot combustion products and heated air from the combustion chamber 37a rise to the top of housing 35 and are admixed above the partition 37 with the flue gas to provide a substantially inert hot gas mixture discharged at the top of housing 35 through conduit 39, which may be employed as lift gas. The quantity of air supplied to the burner may be regulated so that there is no substantial excess of free oxygen in the gaseous products discharged through conduit 39 and the relative proportion of flue gas admitted through line 38 can be controlled to provide a final gas mixture at the desired temperature.

Alternatively the flue gas can be heated by oxidation of CO and other burnable material present therein, taking advantage of the exothermic reaction to raise the temperature of that gas. As disclosed in prior U. S. patent of Eugene J. Houdry, 2,248,994 of July 15, 1941, such oxidation may be effected by addition of an oxidizing medium such as air or by passage of the flue gas over oxygen-supplying catalytic materials. As therein disclosed the gas may be passed over CuO to effect the desired oxidation. Increase in temperature of 200-400° F. or more can be thus effected.

In the use of flue gas as lifting medium, even if suitable arrangements are made for utilization of such gas discharged from a selected region of the kiln at relatively high pressure, it is not always desirable or convenient to operate the kiln at pressures affording flue gas at the required pressure for use as lift gas. It has accordingly been proposed, for instance, in copending application of George D. Myers, Serial No. 124,293, filed October 29, 1949, to raise the pressure of flue gas for use as lift gas by injecting high velocity steam at higher pressure into the flue gas. In doing so, it will be understood, that unless the steam is supplied at a temperature substantially equal to that of the flue gas (or higher), there will be a resulting cooling of the flue gas by the cooler steam injected therein. The practice of the present invention is particularly advantageous in heating up cooled flue gas-steam mixtures thus obtained, to avoid the detrimental effects otherwise encountered in using lift gas which is cooler than the catalyst being lifted thereby. An arrangement for the use of flue gas containing injected steam is illustrated in Figure 3 of the accompanying drawings.

Referring now to Figure 3, there is shown the same arrangement of reactor 10, kiln 12 and lift system as heretofore described, said lift system comprising transfer hopper 14, lift conduit 15, and separating chamber 16. A somewhat modified construction of the kiln is shown in that the lower portion has been flared out and increased in diameter as indicated at 48. By this construction the pressure of the flue gas discharged from the lowermost combustion zone will be relatively higher for any given gas inlet pressure as a result of the reduced height of the bed in such lower zone for a particular bed volume.

Regeneration is effected as in the previous embodiment in two series of vertically superimposed adjacent re-

generation stages through which the catalyst containing combustible deposit flows successively. It will be understood that if desired three or more of such regeneration stages may be employed. Fresh oxygen-containing gas, such as air, is separately introduced into each combustion stage, as shown, through conduits 41 and 42. The gas introduced into the lowermost regeneration stage, through conduit 41, passes upwardly through the bed of catalyst in the widened portion of the kiln, the resulting flue gas being removed through conduit 43. A separate stream of oxygen-containing gas is introduced into the uppermost combustion stage through conduit 42 at a pressure controlled by valve 44 so as to be substantially equal or only slightly greater than the discharge pressure in conduit 43; in practice such difference in pressure may be in the order of 0.1-0.2 lb. per square inch. The oxygen-containing gas introduced by conduit 42 passes upwardly through the bed of catalyst in the upper portion of the kiln and resulting flue gas is removed through conduit 45.

In accordance with this embodiment, the regeneration zone can be operated at comparatively low pressure yet furnish flue gas for use as lift medium. Thus the flue gas discharged through conduit 43 may be substantially below, such as from 10-50% of the static gas pressure at the bottom of the lifting zone in transfer hopper 14. To raise the pressure of the flue gas, it is passed to a steam jet thermo-compressor 46, wherein there is formed a mixture of said flue gas and steam having a pressure higher than that of the flue gas alone and at least equal to the pressure at the bottom of the lifting zone, with suitable allowance, of course, for any pressure drop between the thermo-compressor and the lifting zone. This is accomplished by injecting into the stream of flue gas passing through thermo-compressor 46, high velocity steam obtained by expanding high pressure steam, such as steam at a pressure from about 50 to about 200 lbs. per square inch, from line 47 through the nozzle of the steam jet thermo-compressor. The mixture of steam and flue gas thus formed is thereafter passed through a suitable heater 48 and the hot gas mixture is supplied to transfer hopper 14 into which the mixture enters through supply line 49 and one or more branch lines communicating with the hopper. The heater may be of a design described in U. S. Patent No. 2,248,994, hereinbefore referred to.

Although it will be understood that the same lift hopper arrangement may be employed as that illustrated in Fig. 1, a modified embodiment thereof is illustrated in Fig. 3. Instead of a sleeve sealed off from the solids free space above the catalyst bed in the hopper 14, as in the previous embodiment, there is shown in the present embodiment an open ended sleeve 50 entirely within the hopper, surrounding the lift pipe 15 and extending from a level below that of the catalyst bed in the hopper to a distance somewhat above the catalyst level. A portion of the gas supplied through line 42 passes into the top of hopper 14 by branch line 51 through a control valve 52. The major portion of the gas thus introduced through line 51 will pass down through the annular space 53 between the sleeve and the lift conduit to engage catalyst therebelow and elevate the same into the lift conduit. A minor portion of the gas will pass down through the bed of catalyst outside of the sleeve 50 and then inwardly below the sleeve into the lift conduit 15. Diffuser gas enters the bottom of hopper 14 and below the mouth of the lift conduit through the pipe 54 which is in axial alignment with the lift conduit; admission of gas into pipe 54 is controlled by valve 55.

By injecting from about 0.1 to 1.0 lb. of steam per pound of flue gas, depending on the pressure thereof, the absolute pressure of the flue gas from conduit 43 may be raised to a pressure in conduit 49 such that the ratio of the latter to the former is between about 1.1 to 1.8. In general the steam injected through line 47 may be at a temperature of from about 300° to 400° F. when using dry saturated steam; or the steam may be superheated,

if desired, for instance to about 700-900° F.; the flue gas ordinarily ranges in temperature from about 900-1100° F.

In the event that the amount of flue gas discharged through line 43 is in excess of that required for lifting, a portion thereof may be withdrawn through branch line 57 under control of valve 58, serving to maintain a constant pressure in conduit 43. In this way only that amount of flue gas necessary for lifting is raised to required high pressure and the operations of regeneration and lifting are maintained independent of each other to afford increased flexibility to the system. Under control of valves 52 and 55, the amount of gas supplied respectively to lines 51 and 54 may be adjusted. In some instances it may be desired to permit a slight excess of the mixture of steam and flue gas to enter line 49, in which event such excess may be discharged through a bypass 59 under control of valve 60, which serves to maintain a constant pressure in conduit 49.

By supplying relatively cool air for regeneration through line 41, and with provision for indirect heat exchange in the lower zone of the kiln, the catalyst can be discharged at a temperature lower than that of the flue gas withdrawn through line 43. Thus, in a typical operation the catalyst enters transfer hopper 14 at about 900-925° F. while the flue gas is withdrawn through line 43 at about 1000° F. If there is added per pound of flue gas in the thermo-compressor 0.5 pound of superheated steam at 800° F. the resulting compressed mixture of steam and flue gas will be at a temperature of about 875-900° F. This mixture can be heated to desired temperature in the manner already described.

To obtain the stated advantages of the present invention from the standpoint of improved lift pressure operating efficiency, the lift gas is to be employed at a temperature above that of the catalyst engaged thereby, significantly increased efficiency being realized when the catalyst is at a temperature of 800-1100° F. and the lift gas is at a temperature of 100° F. or more above that of the catalyst. Best practical results are obtained in a lift of uniform cross section over at least the major part of its length, when the lift gas is a temperature of about 200-350° higher than that of the catalyst. To obtain optimum conditions of completely uniform catalyst velocity over a distance of from about the 20 foot level to about the top of a 200 foot straight lift, the over-all temperature of the lift gas should drop approximately linearly in the order of about 400° F. The stated optimum can be achieved only by careful external control of heat transfer which renders such design and operation rather complicated and costly for ordinary commercial installations. Furthermore, if the lift gas temperature is more than about 400° F. above that of the catalyst, the rate of acceleration in the lower portion of the lift will be excessive and may be followed by undesired deceleration higher up in the lift, tending to produce regions of instability. However, the use of lift gas within the above indicated operating range of temperatures above that of the catalyst, can be readily obtained and the described practical advantages realized.

While in the preferred aspects of the invention it is recommended that the lift gas be introduced into the lift at a temperature materially above that of the catalyst, the invention is not intended to be limited thereby. If lift gas is conveniently available at required pressure, as in the case of the steam-flue gas mixture employed in the embodiment of Figure 3, but at a temperature below that of the catalyst, the lift gas may be heated to a temperature equal to or not substantially above that of the catalyst. In thus using lift gas at approximately the temperature of the catalyst, the extremely low efficiency and poor lift operation that otherwise may result from the use of lift gas at a temperature lower than that of the catalyst, are avoided. Thus, it has been found that by using lift gas entering the lift engager at a temperature of 150°-400° F. lower than the catalyst temperature,

lift pressure drop efficiencies of only about two-thirds or less of the normal efficiency (at equal temperature) are obtained.

In lifting granular catalyst at 1050° F. with flue gas as lift medium at respectively: (1) 750° F., (2) 1050° F., and (3) 1350° F., there is a significant difference in the velocity profiles of the catalyst, for the same catalyst mass circulation rate and the same final maximum attained velocity. Thus, in plotting the respective catalyst velocity profiles at various points along the lift in each of the three cases, with distances above the lift inlet as abscissae and calculated catalyst velocity as ordinates, it was found in comparing the velocity curves at levels of 20 to 100 feet above the lift inlet that the curve for the third case (lift gas 300° F. above that of the catalyst) was considerably flatter than the corresponding curves in the other two cases; the slope of that curve in the case of gas hotter than the catalyst in terms of velocity change per unit of height was approximately 0.047 foot per second per foot of height as compared to 0.08 foot per second per foot of height in the case of gas cooler than the catalyst.

In the elevation of granular contact mass such as catalyst by gas in lift conduits of commercially useful size, a certain minimum gas velocity must be obtained to effect desired smooth flow; below such minimum velocity a condition of instability prevails which may be characterized by erratic pressures in the lift, slugging, turbulence, and other factors tending to cause excessive attrition of the solids. In order to minimize these conditions of instability in the lift, gas supply rates ordinarily have to be employed such as to obtain rapid acceleration of the solids to the minimum or critical velocity, obtaining stable flow within a very short distance of travel in the lift; and in doing so, using the required amount of lift gas of comparative high fluid density, the acceleration of the solids is continuously augmented by the progressive reduction in fluid density which may lead to the attainment of undesirably high velocities at or below the discharge outlet of the lift. By the present invention, when using lift gas at a temperature higher than that of the catalyst, advantages are had of the increase in fluid density by loss in temperature of the gas, thus reducing the velocities attained in the lift. Moreover, because of the rapid heat exchange between solids and gas, the effect of reduction in gas temperature is realized in the lower portion of the lift and in the region more likely to be susceptible otherwise to conditions of unstable flow. The effect of heat exchange between the hotter gas and the cooler catalyst is thus beneficially utilized in those regions of the lift where it may be most needed for stabilization of solids flow.

While the application of the invention has been principally described in connection with systems employing lift conduits of substantially uniform diameter throughout, the invention is not limited thereto. Where the lift conduit is uniformly tapered through substantially its entire length by as much as one inch (diameter) per 25 feet of height, the use of lift gas having a temperature of 100° F. or more higher than that of the catalyst offers less advantage than it does in a straight lift. The process of the invention may be employed, to substantial advantage, however, in systems wherein the overall taper is comparatively slight, such as those in which the over-all taper is less than about one inch in 40-50 feet. Moreover, by a strategic choice of lift gas temperature and the appropriate location of suitably tapered sections along the length of the lift pipe, important benefits can be realized from the combined effects to obtain or more closely approach substantially uniform velocities throughout the entire lift height above the small lower portion thereof wherein the catalyst is accelerated to the desired velocity.

I claim as my invention:

1. In a hydrocarbon conversion process in which hot granular contact material gravitates through a downflow

path, including at least one contact zone wherein said granular material is contacted with gaseous material, and in which said granular material is withdrawn from said downflow path and elevated through a confined lift path out of heat exchange relation with said downflow path by lift gas comprising gaseous effluent withdrawn from one of said contact zones at a pressure lower than the desired operating pressure at the bottom of said lift path, the improvement which comprises the steps of: injecting steam at high velocity into said withdrawn gaseous effluent to pressurize the same sufficiently to supply the resultant gaseous mixture to said lift path at said operating pressure, and heating said gaseous mixture to a temperature at least equal to the temperature of said withdrawn granular material before supplying said gaseous mixture to said lift path, thereby preventing such heat exchange between said granular material and said gaseous mixture within said lift path as would effect any substantial decrease in the density of said lift gas.

2. A method as in claim 1 in which at least a portion of said heat is supplied to said gaseous mixture by introducing said pressurizing steam in superheated condition to said gaseous effluent.

3. A method as in claim 1 in which said heating of the gaseous mixture is effected in a separate heating zone.

5
10
15

4. A method as in claim 3 in which said effluent contains carbon monoxide and said heating is effected by the exothermic heat resulting from oxidation of said carbon monoxide to carbon dioxide.

5. A method as in claim 1 in which said withdrawn granular material is at a temperature in the range of about 800-1100° F., and said gaseous mixture is supplied as lift gas to said lift path at a temperature in the range of about 100-400° F. higher than the temperature of said withdrawn granular material.

6. A method as in claim 4 in which said temperature of the gaseous mixture is in the range of about 200-350° F. higher than the temperature of said granular material.
